UNITED STATES PATENT OFFICE.

ANTON J. ROLLERT, OF CHICAGO, ILLINOIS, ASSIGNOR TO THE THEODORE A. KOCHS COMPANY, OF SAME PLACE.

DESIGN FOR A BARBER'S CHAIR.

SPECIFICATION forming part of Design No. 29,848, dated December 20, 1898.

Application filed February 2, 1898. Serial No. 668,895. Term of patent 7 years.

To all whom it may concern:

Be it known that I, ANTON J. ROLLERT, a citizen of the United States, residing at Chicago, in the county of Cook, State of Illinois, have invented and produced a new and original Design for Barbers' Chairs, of which the following is a specification, reference being had to the accompanying drawing, forming part thereof, in which the figure is a perspective view of a chair showing my new design.

As shown in the drawing, the leading or material features of my design consist of a base portion, the legs forming a portion of said base, and the side frames for the seat portion, all of said parts being shaped and ornamented as hereinafter fully pointed out.

In the drawing, A indicates the base, formed, as shown, of a central body portion *a* and legs *b*, projecting therefrom. The body portion *a* is polygonal, and from it at regular intervals project the supporting-legs *b*. The upper edge of each leg at its inner end is concaved, as shown at *c*, at the lower edge of which concave portion is a reversely-curved scroll-like projection *d*, about midway of the length of the leg. The lower portion *e* of each leg is slightly convex on its upper edge and provided on said edge with slight longitudinal grooves, as shown, giving the general appear-

ance of a paw. Projecting from each side of 30 said lower portion *e* of each leg and extending beneath the scroll *d* is a narrow strip *f*.

B indicates the side of the seat-frame of the chair, the prominent feature of which is the production of a rocker-like appearance to the 35 outer face of said frame and the formation at each end of said rocker-like portion of panels *g*, said panels being wider at their upper ends and narrowing by curved lines to a point near the center of the frame *B*. At the ends of 40 the sides *B* are panels *h h'*, arranged below the convex surfaces of the sides, and within said sides are other panels *i*, as shown. The panels *h h' i* are ornamented by carving or otherwise.

It is apparent that the features of my design above set forth are applicable to dentists' and other chairs.

Having described my invention, what I claim as new, and desire to secure by Letters 50 Patent, is—

The design for a barber's chair, substantially as herein described and shown.

ANTON J. ROLLERT.
